WOLFGANG D. RICHTER, OF PHILADELPHIA, PENNSYLVANIA.

WELT MECHANISM FOR FULL-FASHIONED-KNITTING MACHINES.

Application filed June 21, 1927. Serial No. 200,433.

The invention is designed to facilitate the formation of welts on a full fashioned hosiery machine of the cotton type by reducing the amount of manual manipulation of the 5 welt bars and to utilize an improved form of welt hook member whereby the operation is simplified, and whereby also certain automatic actions can take place simultaneously throughout the entire set of sections or 10 heads, thus materially reducing the time and labor ordinarily expended in performing certain hand operations for the formation of the welt, which hand operations, in common practice, take place seriatim through 15 out the whole set of sections or heads of the machine, and while the machine is otherwise idle. In my improvement the welt bars are turned by hand, and placed in a certain position and then by turning over the machine 20 the welt hooks and needles throughout all the sections cooperate automatically and simultaneously to transfer the loops from the welt hooks to the needles, whereafter the welt bars are removed to idle position ready 25 for the next welt forming operation, this removal of the welt bars being performed simultaneously by one act on the part of the operator throughout the whole set of sections instead of individually as is common practice 30 today.

In the accompanying drawings forming part of this specification

Figure 1 is a front view of the upper portion of two sections or heads of a cotton frame with my improvement attached, and with welt bars held by the cradle frames. 35

Fig. 2 is an end view of the improved welt bar.

Fig. 3 is a view of one of the intermediate 40 welt hooks.

Fig. 3^a shows the welt hook in two forms as to the knee.

Fig. 4 is a plan view of the two kinds of 45 welt hooks which alternate in position with each other along the welt bar.

Fig. 4^a is a front edge view of the welt bar.

Fig. 5 is a sectional view taken across a 50 full fashioned knitting machine of the cotton type with my improvements embodied therein.

Fig. 6 is a diagrammatic view of part of the narrowing frame, showing the welt bar placed in initial position engaging the first 55 course of loops.

Figs. 7, 8, 9, 10, 10^a, 11, 11^a, 12 and 13 are

views similar to Fig. 6 showing the elements in various relative positions assumed by them in the turning and formation of the 60 welt.

Fig. 14 is a view of the cradle frame in idle position.

In carrying out my invention I employ a 65 welt turning implement in which the loop engaging hooks and the eyes or grooves for receiving the needles are all located on the same (upper) side of the implement. Further the stems of alternate hook members are provided with humps or knees at the outer ends of the eyes or grooves to define 70 the position of the loops during the welt turning operation, these alternate hook members having other members between them of the same form and arrangement so far as 75 the hooks and the needle receiving eyes are concerned, the exception being that these intermediate members have no humps or knees. Their function is to cooperate with the humps or knees on the stems of adjacent members in definitely determining the location 80 of the loops, it being understood that any tendency for a loop to ride over the hump in the welt turning operation will be resisted by the adjacent loop on the straight intermediate member. 85

My invention includes in addition to this new form of welt turning bar, means by which the whole series of bars can be manipulated simultaneously in connection with their respective sets of needles at the different sections or heads of the machine. This means includes a series of cradle frames 4 for supporting welt bars and moving them simultaneously to cooperate with the needles for transferring the loops thereto. 90

The invention includes other features as 95 will be described hereinafter and pointed out in the claims.

In the operation of the invention a loose course is first formed on the needles. Then 10 the welt bar is placed in position as in Fig. 6 to engage the sinker loops as in ordinary practice with the hooks 1 on the upper side of the welt bar, it being noted, however, that in my improvement, contrary to usual construction, the eye or groove 2 of the hook member is on the upper side instead of on the lower side of the welt hook member. 105

The welt bar in the position just described 110 contacts at its inner edge with the downwardly extending projections 3 of the cradle frame 4. This frame is fixed to a rod or

turnable shaft 5 under tension of a spring 6 tending to swing it forwardly. This tendency, however, is resisted at this stage of the operation because catches 7 on the bar 8 engage pins 9 on the cradle frame and hold the said cradle frame against forward or outward movement.

After all the welt bars have been placed in the position just mentioned with their hooks 10 engaging the loops at the respective sections or heads of the machine, then the catches 7 are released, all simultaneously, by turning the rod or shaft 8 so that the cradle frames at the respective sections are all freed and 15 are then under tension of the spring 6 which now exerts turning force on the rod or shaft 5 to which the arms of the cradle frames are rigidly attached. Each cradle frame now exerts tension on the welt bar placed adjacent 20 it and in contact with its projections 3 thereof and this tension tends to move the welt bar leftward Fig. 6. The machine now can be started and courses are formed, the welt bars receding or moving towards the 25 front of the machine and away from the vertical needles as the courses are formed because of the pressure exerted forwardly by the cradle frames against said bars. This action will be clear by comparing Figs. 6 30 and 7.

The cradle frames can continue to exert this fabric take-up pressure under the action of the spring 6 for enough courses to make say a one inch or more length of fabric. As 35 the welt bars recede from the needles under the pressure of the cradle frames they move along suitable guide or supporting rods placed across the table at the top of the machine as in ordinary practice and as well 40 known to those versed in the operation of this type of machine. During the recession of the welt bars step by step as the courses are being formed, the operator has time enough to attach the usual elastic straps 10 45 Fig. 8 to the welt bars along the entire length of the machine. Ordinarily this action of attaching the elastic straps to the welt bars takes place while the machine is idle and no courses are being formed and 50 this occasions considerable expenditure of time during which there is no production of fabric taking place, the operator having to go from section to section and attach the elastic strap at each section individually. In my 55 apparatus this attaching of the straps takes place while the welt bars are still within the range of action of the cradle frames which can swing forwardly for a considerable distance and still exert take-up pressure upon the welt bars. Thus a considerable number of courses can be formed while the welt bars are under the influence of the spring pressed cradle frame and ample time is given for the operator to attach the 60 elastic straps to the welt bars so that these 65

straps will be ready to take the place of the cradle frames as a means for exerting take-up tension upon the welt bars. A gain of a considerable number of courses is thus effected at each section of the machine, and as 70 there are say twelve heads with two sets of fabric producing elements at each head, the aggregate increase in production over the ordinary method of operation is material.

After the elastic straps are attached to 75 the welt bar as in Fig. 8 the take-up tension supplied to the welt bars by the cradle frames is no longer needed and therefore the cradle frames are pressed back all simultaneously, as they are all hung from the 80 same rotary rod 5, and they are held in their rear or pressed back position by the catches 7 of the bar 8, which catches engage the projections 9 of the cradle frames as before mentioned.

There may be two of these catches for each cradle frame.

After the straps are attached and the cradle frames have been pushed back and locked, the machine continues the formation 90 of courses until the desired length of fabric is produced for the turning of the welt. The needle bar is now moved forward carrying the vertical needles from the knock over bits i. e. from the position shown in Fig. 8 95 to the position shown in Fig. 9, whereupon the needle bar moves downward and then inward to carry the end fabric loops (x) to a position below the knock over bits and the needles themselves are now positioned 100 with their noses between the knock over bits, see Fig. 10. In arriving at this position of the parts shown in Fig. 10 from the position shown in Fig. 9 the machine is turned 105 backwards.

The elastic straps are unhooked from the welt bars and said bars are turned by hand from the position shown in Fig. 9 to the position shown in Fig. 10, in which position the welt hooks have been moved through 110 the loops.

The loops are by this action changed in position from the hooks of the welt implements onto the stems thereof and against the knees 11 and in rear of the groove or 115 eye 2 in the said stems.

Previous to turning the welt bar an elastic strap holding welt rod 12 was placed, as in ordinary practice, on the upper side of the fabric which is to be turned for the 120 formation of the welt. This bar in the subsequent knitting operation places tension upon the fabric.

The welt bar is now placed in the cradle frame see Fig. 11 with its ends 13 Figs. 1 125 and 4^a held in position by the spring arms or clips 14 extending upwardly from the rests or ledges 15 upon which the welt bar is supported. The position of the welt bar as thus placed is determined and insured as to 130

accuracy by end shoulders at 13* on the welt bar fitting against the adjacent sides of the depending arms 4 of the cradle frame, see Fig. 1. This position is such that the welt hooks will be in accurate alignment with the needles with which they are to cooperate. The cradle frame is now lowered so that the welt hooks enter between the knock over bits and the grooves of the stems of the hooks 5 come over the upper ends of the needles as shown in Figs. 11 and 11^a, which needles as stated above have been moved forwardly, downwardly and rearwardly so that their upper ends lie between the knock over bits 10 and their fabric loops *x* are below the said knock over bits having been carried down by the friction of the downwardly moving needle. 15

The line of fabric loops (*x*) is now below 20 the plane in which the welt hooks are located so that there is no danger of the hooks engaging these loops or the fabric.

The sinkers now move forward from the position shown in full lines Figs. 11 and 11^a, 25 to the position shown in dotted lines and thus arrive in position above the loops on the welt fingers. The needle and welt hook are now in the relative position shown in Fig. 11^a with the nose of the needle pressing 30 against the bottom of the groove or eye 2 of the stem of the hook.

It will be noted also that at this time the loop on the welt finger or member is located just below the knee 11. That is to say, the 35 knee overlies the loop and has determined its position so that the sinker can get in position above the line of loops by advancing to the dotted line position Figs. 11 and 11^a. After assuming this position the welt hook and the 40 needle both move upwardly in unison and the needles pass through the loops which are now held against upward displacement by the overlying sinker. The welt hook has raised with the needle to the point where the 45 loop is below the needle beard and the operation of transferring the loop from the welt hook onto the needle is thus completed.

In the action just described the welt hook 1 lies at the back of the needle, at the widest 50 part of the needle stem. The welt hook is thus shielded by the needle and its safe passage upward through the loop is insured. The welt hook is now outside the welt loop and the needle stem now carries two loops 55 i. e. the fabric loop *x* and the loop *y*, both of which will be cast off into the fabric at the next knitting operation and the work of forming the fabric of the leg will now be proceeded with as in ordinary practice.

60 It will be noted from Figs. 11 and 11^a that when the needle receives the loop from the welt hook the fabric loop *x* is still below the knock over bit, and in order to knit this loop into the fabric it must be disposed at a 65 point above the knock over bit. For getting

the loop *x* into this last mentioned position the needle bar moves outward so that the needles are moved from between the knock over bits. The position of the parts is now as seen in Fig. 12, the loop *y* still being under the sinker. The needles and welt bar now rise and the friction of their stems on the loops *x* causes the stems to carry the loops *x* up to a level above the knock over bits as seen in Fig. 13, and the needle now having 70 moved back again to the right to normal position between the knock over bits and both loops *x* and *y* are above said knock-over bits ready to be cast off at the next knitting operation. 75

Previous to proceeding with the regular knitting, however the cradle frames as a set are swung up by hand to a position out of the way where they remain during the knitting of the remainder of the stocking leg, 80 and until the next welt is to be performed. All the cradle frames are swung up by one act on the part of the operator, all of said frames being mounted on the same rod 5 and moving in unison either up or down when 85 the operator applies force by hand to said frame at any point along the machine. 90

When swung to its upper position see Fig. 14 the cradle frame turns through an arc of approximately 180° so that the ledge or rest 16 now faces upwardly in horizontal position instead of downwardly. When the cradle frames are lifted the welt bars naturally go with them and when a certain point in the upward swing is reached the 95 welt bars will slide by gravity out of engagement with the spring clips 14 and as the upward movement of the cradle frame continues the bars will slide relative to said cradle frames until they will finally rest on the ledges 16 and they will thus be in position out of the way during regular knitting, yet accessible to the hand of the operator who picks them up from these ledges 100 when the next welt is to be formed. 110

It will be noticed that the cooperative relation between the welt hooks and the needles takes place between the knock-over bits. This insures proper engagement of these parts, the knock-over bits furnishing side 115 walls to the spaces in which the needles and welt hooks connect with each other.

It will be seen also that the welt hook is at the back of the thick part of the needle which thus prevents the welt hook from engaging with the loop. In other words the needle lies between the loop and the welt hook so that the said hook can be readily withdrawn from the loop. 120

The cradle frame is carried by the well known narrowing apparatus of the machine indicated generally at 17 and is given the requisite movements to operate the cradle frame up and down by suitable cams on the cam shaft. 125 130

The needle bar is given its special movement by cams on the cam shaft. For this purpose a shifting mechanism is provided whereby certain rollers may be brought into line with cams for giving the parts these special movements (see the shiftable forks indicated at 18—19 Fig. 5). These same rollers when not shifted but in regular working position are operated by the ordinary cams for giving the parts their regular movements.

The cradles are suspended from the upper bar 20 of the narrowing apparatus and for giving the cradle the movements upwardly and downwardly necessary to carry out the operation above described, the narrowing mechanism is given the necessary movement by a cam on the cam shaft. The narrowing apparatus is operated as in usual practice to perform the narrowing operation by a link L, a lever m operated by a cam through a roller n. Now in order to give the narrowing apparatus the special movement to carry out the present invention the roller n is shiftable axially into line with another cam which will give the desired movement.

This special cam is shown at Z, Fig. 5. It has a high point e which through roller n, lever m and link l raises the narrowing frame to the position at which the welt bars are inserted in the cradle frames, as indicated in Fig. 5. f indicates the low point on this cam to bring the welt bar down with the eyes or grooves in the hooked member of the welt bar to receive the upper ends of the needles. The needle bar and the narrowing apparatus rise together and when the point g of cam Z comes into action, the transfer of loops is completed and the cradle frame now can be thrown up to idle position to carry the welt bar with it, where it remains as shown in Fig. 14 until the next stocking is to be knit.

The needle bar N is given up and down movement by a bell crank lever o from a roller p¹ operated by the ordinary needle bar cam indicated at u.

For giving the needle bar its forward and backward movements to carry out the new action involved in this invention, the presser cam P is employed. This cam has three points of importance. The low point a throws the needle bar out into the position shown in Fig. 9, preliminary to locating the loops on said needle below the knock-over bit. For this purpose the roller q' cooperates with this cam when shifted into line therewith. Said roller is carried by pivoted lever q, which is connected with the needle bar through link r, and the depending arm r¹. The next point is the high point C, which brings the needles, when lowered, to the position shown in Figs. 5 and 10, i. e., with their upper ends between the knock-over bits, in position to allow the setting of the welt

bar in the cradle frame with its hook members above and in front of the needles, Fig. 10. The next point is c on said presser cam P, which throws the needle out again and presses the needle against the welt instrument which has been lowered into position as shown in Figs. 11 and 11^a, and into the groove or eye thereof. The needle bar now goes up with the welt implement and the loops get below the beard. The point d on 75 the presser cam next comes into action, moving the needle bar with the needles outwardly as shown in Fig. 12, and the loop x is now carried up by the friction of the needle stem above the plane of the knock-over bit, 80 whereupon the point d¹ comes into action and the needle is moved inwardly to locate loop x above the knock-over bit, thus bringing the fabric to its original position and the knitting of the stocking leg now can be carried on. 85

The rollers n and q' are shiftable into line with the special cams Z and P by forks 19 which may be operated in the direction of the axes of these rolls in any suitable manner. For instance, such forks may be mounted on a rod w which is suitably mounted and is shiftable in the direction of its axis.

For convenience of illustration, the springs 95 14 are shown as engaging the body of the welt bar.

I claim:

1. A welt turning implement for full fashioned knitting machines having hooks 100 for engaging the loops, and grooves or eyes adapted for receiving the nose of the needles all on the upper side of said implement, substantially as described.

2. A welt turning implement for full 105 fashioned knitting machines having terminal hooks, for engaging the loop, grooves or eyes adapted for receiving the nose of the needles and humps for positioning the loops, said hooks and eyes being located on 110 the upper side of said implement, substantially as described.

3. A welt turning implement for full fashioned knitting machines having upwardly facing hooks and upwardly facing 115 needle receiving grooves or eyes and loop positioning humps, said stems alternating with other stems having similar hooks and eyes but no humps, substantially as described.

4. A welt turning mechanism for full fashioned machines comprising in combination welt bars having members each with a hook to engage the loop, and an eye in the stem of the member back of the hook and on the same side of the member with the hook, a frame for receiving and removably supporting all the said welt bars, said frames presenting said welt bars to the needles initially with the hooks of said welt 120 125 130

- bars at the back of the needles and with the eyes of said hooked members receiving the nose of the needles, and means for operating the said frames and needles to effect the transfer of loops to the needles, substantially as described.
5. In combination with welt bars having hooked members with eyes on the upper side thereof tension straps, frames under spring tension for applying a take-up tension to the said welt bars while a number of courses are being knit, and while said tension straps are being attached, said frames being adapted for holding said bars, and presenting the hooked members to the needles with the hooks at the back of the needles and the eyes receiving said needles, and thereafter having movement together with the needles for transferring the loops from the hooked members onto the needles, substantially as described.
10. In combination with welt bars having hooked members with eyes on the upper side thereof tension straps, frames under spring tension for applying a take-up tension to the said welt bars while a number of courses are being knit, and while said tension straps are being attached, said frames being adapted for holding said bars, and presenting the hooked members to the needles with the hooks at the back of the needles and the eyes receiving said needles, and thereafter having movement together with the needles for transferring the loops from the hooked members onto the needles, substantially as described.
15. In combination in a full fashioned knitting machine, welt bars having hooked members for engaging the loops, supports for receiving and removably holding the welt bars after the prescribed length of fabric has been knit for the welt, said supports being connected with the narrowing apparatus of the machine, said narrowing apparatus having movement with said supports to present the hooks to the needles for the transfer of loops by the subsequent co-related movement of said parts in cooperation with the sinkers, substantially as described.
20. In combination in a full fashioned knitting machine, a series of welt bars, one for each section, supports for said welt bars to present the hooked elements thereof to the needles for transfer of loops, said supports being under spring tension, and applying take-up tension to the welt bars while a series of courses are being knit and before said welt bars are placed on said supports, substantially as described.
25. A full fashioned knitting machine according to claim 7, having means for retaining the spring pressed supports in position to present the welt bars to the needles, substantially as described.
30. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
35. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
40. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
45. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
50. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
55. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
60. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
65. In combination in a full fashioned knitting machine, welt bars having hooks, supports for said welt bars pivotally mounted and under spring tension to apply take-up tension to the welt bars while a number of initial courses are being knit for the welt, means for locking said supports in retracted position and means for moving said supports to present the welt bars to the needles for the transfer of loops thereto, substantially as described.
70. In a full fashioned knitting machine, welt bars, frames pivotally mounted, and biased to move outwardly from the needles and engaging the welt bars to apply take-up tension thereto, during the knitting of the welt courses, said frames being adapted to support the welt bars during transfer of loops and from which frames said welt bars are removable substantially as described.
75. In combination in a full fashioned knitting machine, welt bars having hooks to engage the loops, frames applying take-up tension to said bars during the knitting of the welt courses and for holding the welt bars to present them to the needles for transfer of loops thereto, said frame being pivotally mounted to be swung to idle position and adapted to hold the welt bars, when idle, removably in position readily accessible to the hand of the operator, substantially as described.
80. A full fashioned knitting machine according to claim 12 in which the pivoted frame is carried by the narrowing apparatus and is operated thereby to and from the needles, substantially as described.
85. A full fashioned knitting machine according to claim 12 in which the pivoted frame is carried by the narrowing apparatus and is operated thereby to and from the needles, substantially as described.
90. In a full fashioned knitting machine and in combination needles which are moved outwardly, downwardly and inwardly to carry the loops thereon from over the knock over bits to a position below said knock over bits, welt bars having hooked members with eyes or grooves which are moved to receive the needles in said grooves and with the hooks at the backs of the needles, sinkers which are moved over the loops carried by the hooked members, said hook members and needles being moved upwardly to remove the hooks from the loops, and to pass the needle beards through the loops, substantially as described.
95. A full fashioned knitting machine according to claim 14 in which the engagement of the hooked members with the needles takes place between the knock over bits, substantially as described.
100. The hereindescribed method of turning a welt on full fashioned stockings consisting in connecting by hand welt bar hooks with the loops of the first course, applying tension to the whole series of welt bars simultaneously throughout the length of the machine during the knitting of the welt courses, thereafter placing by hand said welt bars carrying the loops in prescribed relation to their respective sets of needles, holding the loops of the hooked members at one level by the sinkers and moving the needles and welt bars simultaneously throughout all the sections or heads of the machine to pass the needle beards through the loops and to disengage the hooked members from the loops, substantially as described.
105. The hereindescribed method of turn-

ing a welt on full fashioned knitting machines consisting in attaching welt bar hooks to the initial loops, moving the needles to carry said loops below the knock over bits, 5 after the prescribed number of courses have been knit, placing all the welt bars for all sections or heads of the machine in their prescribed relation to the needles, holding the loops on the welt hooked members at one 10 level by sinkers and above the knock over bits, moving all the welt bars and all the sets of needles simultaneously and similarly to pass the needle beards through the said loops and withdraw the hooked members from said 15 loops, then moving the needles to carry fabric loops from below the knock over bits to a position above said knock over bits and adjacent the loops just taken on by said

needles, and then proceeding with the knitting of the fabric, substantially as described. 20

18. The herein-described method of turning a welt on full fashioned knitting machines consisting in attaching hooked welt bar implements to the initial loops, placing said implements over the needles with the 25 hooks of said implements at the backs of the needles and with the nose of the needles entering eyes in the implements located adjacent to the hooks thereof, and on the same side of the implements therewith, and then transferring the initial loops from the welt implements onto the needles, substantially as described. 30

In testimony whereof, I affix my signature.

WOLFGANG D. RICHTER.
